United States Patent Office.

F. F. LAHM, OF CHICAGO, ILLINOIS.

Letters Patent No. 96,446, dated November 2, 1869.

IMPROVED SPRING-BED BOTTOM.

The Schedule referred to in these Letters Patent and making part of the same.

To all whom it may concern:

Be it known that I, F. F. LAHM, of Chicago, in the county of Cook, and State of Illinois, have invented a new and useful Improvement in Spring-Bed Bottom; and I do hereby declare that the following is a full, clear, and exact description thereof, which will enable others skilled in the art to make and use the same, reference being had to the accompanying drawings, forming part of this specification.

This invention relates to a new and useful improvement in spring-bottoms for beds and sleeping-couches, and consists in the springs, and in the construction and arrangement of parts, as hereinafter described.

In the accompanying drawing—

Figure 1 represents a vertical cross-section of the spring-bottom, through the line $x x$ of fig 2.

Figure 2 is a top or plan view.

Similar letters of reference indicate corresponding parts.

A represents the bedstead.

B represents metallic boxes, which are screwed fast to the posts of the bedstead, from which boxes the spring-bottom is supported.

The bottom consists of a lower transverse rail, C, an upper transverse rail D, and the springs E F placed between the upper and the lower rails C and D.

G represents the longitudinal slats, which are let into the lower rails C, as seen in fig. 1.

These rails (with the slats G) are attached to the lower spring F, by means of the bands H H.

The two springs at each end of the bottom are confined together at their ends by the bands I I.

The upper spring E is connected with the upper rail D by the bands J J.

The ends of the rail D extend outward on each side, over the ends of the springs, sufficiently far to rest in the boxes B, as seen, so that the bed-bottom is suspended therefrom, while the rails and the springs are held together by the bands before mentioned.

These bands are movable to or from the centre, so that the elasticity of the springs may be increased or diminished, as may be desired. The springs may be made of either wood or metal. The transverse rails and longitudinal slats are of course made of wood of any suitable kind.

By this arrangement, a very durable and highly elastic bottom is formed suitable for all kinds of beds and sleeping-couches of all descriptions.

Having thus described my invention,

I claim as new, and desire to secure by Letters Patent—

1. In combination with a bed or couch-bottom, the springs E and F, confined together and to the rails of the bottom, by adjustable bands, as shown and described.

2. The combination of the rails D C and slats G with the springs E F, arranged and operating substantially as described and for the purposes set forth.

F. F. LAHM.
